[57] CLAIM

The ornamental design for a communication apparatus enclosure, substantially as shown and described.

DESCRIPTION

FIG. 1 is a front, top and side perspective view of a communication apparatus enclosure including a front cover showing our new design;

FIG. 2 is a front elevational view of the enclosure as shown in FIG. 1;

FIG. 3 is a side elevational view thereof, the side opposite to it being a mirror view of the side shown;

FIG. 4 is a rear view thereof;

FIG. 5 is a top plan view thereof; and

FIG. 6 is a bottom view thereof.

FIG. 1

FIG. 3

FIG. 2

FIG. 4

FIG. 5

FIG. 6
